UNITED STATES PATENT OFFICE.

HENRY LISI, OF SUSQUEHANNA, PENNSYLVANIA.

DOUGHNUT-COOKING MACHINE.

Application filed September 9, 1921. Serial No. 499,387.

To all whom it may concern:

Be it known that I, HENRY LISI, a citizen of the United States, residing at Susquehanna, in the county of Susquehanna and State of Pennsylvania, have invented certain new and useful Improvements in Doughnut-Cooking Machines; and I do declare the following to be a full, clear, and exact description of the invention, such as will enable others skilled in the art to which it appertains to make and use the same.

This invention relates to an improved machine which is especially, but not necessarily, designed for cooking doughnuts and the like.

The principal object of the invention is to generally improve upon machines of this class by providing one of extreme simplicity and durability which is practical in operation, sanitary, strong, durable and comparatively inexpensive to both the manufacturer and the user.

Another and a very important object of the invention is to construct a machine of this class embodying an openwork basket for containing the doughnuts, this basket being positioned in the hot grease container and there being novel hoisting means associated with it for raising it to a position where its contents can be dumped into a receiving tray.

Another object of the invention is to provide a machine embodying the aforesaid structure together with an open work cover for the basket, this cover having means associated with it for raising it to a vertical position and retaining it in such position so that it will be entirely out of the way of the basket when the latter is raised.

Other objects and advantages of the invention will be apparent during the course of the following description.

In the accompanying drawings forming a part of this specification and in which like numerals are employed to designate like parts throughout the same,

Figure 1 is a side elevational view, with parts broken away and shown in section, of a machine constructed in accordance with this invention, showing, in dotted lines the position that the basket and cover take when the doughnuts are being dumped.

Figure 2 is a top plan view of the machine.

Figures 3 and 4 are enlarged transverse sectional views taken substantially on the

planes of the lines 3-3 and 4-4 respectively of Fig. 1.

Referring to the drawings, it will be seen that the machine comprises a suitable support, which is here shown as including legs 1 connected together at their upper ends by longitudinal side rails 2 and cross-pieces 3. Positioned between the side rails is an open bottomed metallic flame guide 4 which is designed to direct the flames from the burner 5 against the bottom of the removable grease pan 6. It is to be noted that the upper edges of the grease pan are bent laterally to form flanges 7 and these flanges rest on the parts 2 and 3 of the support. Also arranged on the support is a receiving pan 8 which is supported on the cross-pieces 3 and has its open end down-turned as indicated at 9 to direct any grease which may be deposited therein back into the grease pan. The doughnut container is designated by the numeral 10 and is here shown in the form of a wire basket, although it may be of any other construction such as would permit the grease to drain from it as it is lifted for removing the doughnuts. It has been before indicated that means is associated with this basket for raising it to the dotted line position indicated in Fig. 1, for the purpose of dumping the doughnuts therefrom into the receiving tray 8. While various constructions may be provided for accomplishing this end, I prefer to make use of a manually operated hoisting device which includes

a rock-shaft 11 to which a pair of arms 12 are connected, these arms being curved inwardly toward each other at their outer ends and being directed downwardly as indicated at 13 and connected together by a bar 14 which is in turn connected to one end of the basket and serves as a sole supporting means for the latter. Also connected with the rock-shaft 11 is a handle 15, which, when grasped and swung upwardly carries the parts 12 and 14 upwardly so that the basket

will be moved to the dotted line position indicated in Fig. 1 to enable the doughnuts to be dumped therefrom.

It is desirable, as before intimated, to employ a cover 16 for the basket. This cover is preferably composed of wire and has means associated with it for swinging it to a substantially vertical position and maintaining it in such a position so that it will not interfere with the upward movement of

the basket and will permit the latter to be conveniently filled with uncooked doughnuts. This leads me to say that it is of course understood that the usual pivotally mounted cutting and mixing machine is arranged over the top of the machine shown in the drawings to permit the uncooked doughnuts to be dropped into the hot grease. The means for arranging the cover in the aforementioned manner comprises in its preferred form, a rock-shaft 17, a bar 18 which is connected to one end of the cover, a crank arm 19 to be connected to the rock-shaft and bar and means for rotating the rock-shaft and maintaining it against movement. It is to be stated that the bar 18 is properly shaped to extend over the side rails of the supporting frame and positioned to cross the basket which is disposed below the rock shaft and side rails. Referring now to the means for imparting rotation to the rock-shaft 17 and holding it in a set position, it will be seen that this means comprises a handle 20 which is pivoted intermediate its ends on the rock shaft and has a small rod 21 pivotally connected to one end, this rod having its free end connected to a guide 22 on one of the legs of the supporting structure and there being a coiled spring 23 surrounding the rod between the stop 24 on the latter and the aforesaid guide. With this arrangement, it will be seen that by grasping the handle 20 and moving it upwardly to the dotted line position indicated in Fig. 1, the rod 21 will have passed beyond "dead center" and will lock the parts in a position to which they have been moved and will maintain them in such position until returned to operative position by hand.

Assuming that the basket is in operative position and that the cover is in the inoperative dotted line position indicated in Fig. 1, it will be seen that the uncooked doughnuts will be dropped from the cutting machine into the hot grease and after a sufficient number have been dropped, the handle 20 will be grasped and the cover 15 swung down into the grease and over the open side of the basket and confine the doughnuts therein while cooking. After the latter have been cooked to the desired degree, the handle 20 is again grasped and moved upwardly. As before indicated, this will cause the cover to move upwardly and be locked in a position where it will not interfere with the upward movement of the basket. To move the basket upwardly, it is only necessary to grasp the handle 15 and lift it to impart rotation to the rock-shaft 11. In so doing, the parts 12 and 14 are lifted and inasmuch as they are connected with the basket, the latter is swung upwardly to a substantially vertical position and at the same time is positioned over the receiving tray into which the cooked doughnuts are deposited.

By carefully considering the description in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the subjoined claims may be resorted to if desired.

I claim:

1. A device of the class described comprising a support, a grease pan, an open-work basket for holding the articles to be cooked, said basket being arranged in said pan, hoisting means connected with one end of the basket for raising it to dumping position, a cover for the basket, and means for raising said cover to and holding it in a vertical position to permit the basket to be raised.

2. A device of the class described comprising a support, a grease pan, an open-work basket for holding the articles to be cooked, said basket being arranged in said pan, a substantially U-shaped frame having its intermediate portion connected with one end of said basket, a rock-shaft to which the free ends of the arms of the frame are connected, and a handle connected with said shaft.

3. A device of the class described comprising a support, a grease pan arranged thereon, an openwork basket for holding the articles to be cooked, said basket being arranged in said pan, a rock shaft rotatably mounted on said shaft, arms connected with said shaft and extending laterally from it, the outer ends of said arms being curved inwardly toward each other and downwardly and being connected together, the connected portion thereof being connected to one end of said basket, and a handle connected with said rock shaft for imparting rotation to the same.

4. A device of the class described comprising a support, a grease pan mounted on said support, a basket arranged in said pan, a cover for said basket, a rock shaft, a crank arm connected to said rock-shaft, a bar connected to said crank arm and with said cover, and means connected with said shaft for rotating it and maintaining it in a set position.

5. A device of the class described comprising a support, a grease pan, a basket arranged in said pan, a cover for said basket, a rock shaft mounted on said support, means for connecting said cover with said shaft, a handle connected between its ends with said shaft, a rod pivotally connected with one

- end of said handle, a guide through which said rod passes, a stop on said rod, and a coiled spring surrounding the rod between said stop and guide.
- 5 6. In a doughnut cooking machine of the type specified, means for raising and maintaining a basket cover in a vertical position to permit raising of the basket, said means comprising a rock shaft, a connection between the cover and said shaft, a handle connected with the shaft, a rod pivotally connected with the handle, a guide through which said rod passes, a stop on the rod, and a coiled spring surrounding the rod between the stop and the guide.
- 10 7. In a doughnut cooking machine of the type specified, means for lifting a basket to dumping position comprising a substantially U-shaped frame, the intermediate portion of which is adapted to be connected with one end of the basket, a rock shaft with which the free ends of the side arms of the frame are connected, and a handle connected with said shaft for rotating it.
- 15 20 25 8. A doughnut cooking machine comprising a support, a flame guide arranged thereon, a grease pan arranged inside of said flame guide, an openwork basket for holding the articles to be cooked, said basket being arranged in said pan, hoisting means for the basket comprising a frame connected with the basket, a rock shaft to which the arms of the frame are connected, and a handle for rotating said shaft, a cover for said basket, and means for raising said cover to a vertical position to permit the basket to clear it when the latter is raised to dumping position, said raising means for the cover comprising a rock shaft, a connection between the rock shaft and said cover, a handle connected with said rock shaft and cover, a rod pivotally connected to the lower end of the handle, a guide through which said rod is slidible, and a spring cooperative with the guide and rod for maintaining said cover elevating means in operative position.
- In testimony whereof I have hereunto set my hand.

HENRY LISI.
